UNITED STATES PATENT OFFICE.

HARRY J. SEAMAN, OF CATASAUQUA, PENNSYLVANIA.

DUST-SEPARATING AND STEAM-GENERATING APPARATUS.

1,185,135.

Specification of Letters Patent.

Patented May 30, 1916.

Application filed December 4, 1914, Serial No. 875,568. Renewed January 18, 1916. Serial No. 73,070.

To all whom it may concern:

Be it known that I, HARRY J. SEAMAN, a citizen of the United States, and resident of Catasauqua, county of Lehigh, and State of Pennsylvania, have made a certain new and useful Invention Relating to Dust-Separating and Steam-Generating Apparatus, of which the following is a specification, taken in connection with the accompanying drawings, which form part of the same.

This invention relates especially to apparatus for separating the suspended particles of dust or fumes from the furnace gases discharged from rotary cement kilns or other furnaces and at the same time utilizing the heat contained in these furnace gases for the generation of steam. The apparatus preferably comprises a boiler containing a number of large area vertical tubes through which the hot furnace gases are passed preferably in a downward direction and there is also arranged within each of these gas tubes or heating passages one or more highly charged electric conductors which by their electrostatic action separate from the gases dust and fumes and cause their collection on the inside of these tubes, while at the same time promoting the transmission of the heat in the gases through the convection effects caused by these high potential charges.

In the accompanying drawing showing in a somewhat diagrammatic way an illustrative embodiment of this invention Figure 1 is an elevation partly in section; and Fig. 2 is a transverse sectional view taken substantially along the line 2—2 of Fig. 1 and looking upward.

By way of illustration the apparatus is shown as arranged in connection with a rotary Portland cement kiln from which the dust laden gases are discharged at temperatures of about 1000 degrees Fahrenheit or so, although it is of course understood that hot furnace gases from any other metallurgical or other furnace may be treated in this apparatus. The cement kiln 1 may have the usual steel shell and bearing rings 2 and may be provided with a lining 3 of fire-brick or other suitable material adapted to withstand the high working temperatures. The lower end of this slightly inclined kiln which is rotated by any suitable means preferably projects within the firing hood 4 formed or lined with masonry or the like which may advantageously form a sub-

stantially tight joint with the kiln as by interposing a suitable flange 5 and coöperating washer 6 on these parts as indicated. The feeding apparatus for the fuel, when powdered coal is used may comprise the coal bin 13 and connected feed screw 12 which may deliver the coal in regular measured quantities into the upper end of the coal injector 9 from which it is blown by the high pressure or other blast of air supplied by the air pipe 11 so as to form a compact stream of suspended powdered coal and air and drive the same substantially axially up the kiln for efficient combustion. The raw cement material consisting of the finely pulverized mixture of argillaceous material may be fed into the upper end of the kiln in any desired way and gradually passes down through the rotating kiln in which it is first calcined and then clinkered or fused into rough granular balls or masses which are discharged at white heat into the hood and may pass through the clinker chute 14 through which air may be drawn for combustion in the kiln and be more or less heated by the hot clinker.

The upper end of the kiln may coöperate with the housing 7 preferably forming a substantially tight joint therewith and leading the hot furnace gases through the gas conduit 8 into one or more suitable dust separating boiler units where the dust and fumes may be removed to the desired extent by any suitable electrostatic devices preferably increasing the heat transfer action.

As indicated this boiler dust separator unit, of which any desired number may be connected to a single cement kiln so as to be used simultaneously or in alternation as desired, may have a steel shell such as 20 of any desired size, shape and construction and provided with a heavy lagging 21 of asbestos or other heat-insulating material. This boiler shell may be conveniently formed as a cylindrical shell vertically arranged and provided with tube sheets such as 27, 28 secured in position in any desired way so as to form a gas chamber 22 above the tubes and a collecting chamber 23 below them of ample capacity to allow for the settling and collection of the dust before the gases are discharged through a suitable discharge flue, such as 25. Gas tubes of any desired shape and construction may be provided for the passage of the hot furnace gases and if desired the vertical cylindrical tubes 29

which are mounted within these tube sheets may have the unusually large diameter of ten to fifteen inches or so and a length of ten to twenty feet according to the conditions of operation. These tubes of welded steel, for instance, may have their ends expanded or otherwise secured in position in the tube sheets preferably having one or both ends projecting considerably beyond the same, the lower ends 32 of these tubes being shown as projecting six or eight inches or more below the tube sheets and being reinforced at this point for engagement with the strikers or dislodging devices used from time to time to dislodge the dust from the inside of the tubes. These strikers 33 may be in the form of blocks or members of steel or other material mounted on the curved spring or other resilient arms 34 by which they are connected to the striker rods 35 extending transversely through the collecting chamber and geared together or otherwise simultaneously oscillated from time to time so as to forcibly bring all these strikers in connection with their coöperating reinforced tube ends and thus cause sufficient impact and vibration effects throughout the tubes to dislodge the adherent coating of dust from their inside surface. Under these conditions the dust falls to the bottom of the collecting chamber from which it may be removed as by the screw conveyer 24, this settling action being facilitated by momentarily shutting off the supply of gases to the apparatus as by entirely or partly closing the cut-off valve 36 and taking care of the kiln gases in some other way.

The gas tubes 29 may be provided with one or more electric conductors, such as 30, within each tube and if desired extending substantially centrally throughout the same. These conductors may be connected to the supporting rods or conductors 31 at either end of the tube which may be supported and insulated in any suitable way and kept charged with electricity at the desired high potential of 30,000 to 50,000 volts or more by a rectifying transforming apparatus supplying such high tension electric current of a uni-directional or substantially constant character. These electrified conductors effect the rapid separation of the particles of dust and fumes from the furnace gases passing through these separating tubes, the particles of dust being driven by electrostatic action outward toward the walls of the tube and adhering thereto or falling down through the tube to the bottom of the enlarged collecting chamber below so as to be removed therefrom by the discharge conveyer 24 and utilized as by the recovery of potash and reburning the residue in cement kilns or otherwise in the case of the dust separated from cement kiln gases. This separating action is considerably promoted by

passing the furnace gases downward through these separating tubes and also by simultaneously cooling them which correspondingly reduces the volume and velocity of the gases and considerably promotes the separation of dust particles therefrom. The highly charged electrostatic separating elements also cause convection effects in the hot gases and thus promote the transfer of heat from the gases to the tubes and to the surrounding steam and water. At the same time the temperature of the steam in ordinary boiler practice is considerably above the temperature at which any water vapor can condense in the furnace gases passing through these heating tubes at atmospheric pressure so that the electrical action of the apparatus is not impaired. It is furthermore, possible to secure still greater utilization of the heat in the gases by using them to generate steam at low pressure and correspondingly lower temperature so that the tube walls may be kept as low as a few hundred degrees Fahrenheit where the steam is generated at five to ten pounds pressure or so per square inch and utilized for steam turbine work to supplement the exhaust from other steam engines, for example. In this way a large proportion of the heat in the kiln gases may be utilized and at the same time the efficiency and thoroughness of the dust separation increased.

This invention has been described in connection with a number of illustrative embodiments, forms, proportions, materials and arrangements of parts, to the details of which disclosure the invention is not of course to be limited, since what is claimed as new and what is desired to be secured by Letters Patent is set forth in the appended claims.

I claim:

1. In apparatus for separating the dust from the hot gases discharged from rotary Portland cement kilns and for generating steam therefrom, a vertically arranged cylindrical boiler shell provided with internal tube sheets to form a gas chamber adjacent the top of the shell and an enlarged collecting chamber adjacent the bottom of the shell, a discharge conveyer extending into said collecting chamber to discharge the dust collected therein, a gas conduit communicating with said gas chamber to supply hot furnace gases from a rotary cement kiln to said gas chamber and cause their passage down through said gas tubes and supply heat to the water around said tube, a discharging flue for said gases communicating with said collecting chamber, large diameter vertical gas tubes mounted in said tube sheets and having reinforced ends extending below the lower tube sheet, strikers resiliently mounted on oscillating striker rods to coöperate with said reinforced tube

ends and dislodge the adherent dust within said tubes and highly charged electric separating conductors extending substantially axially through said tubes separating the suspended dust from the furnace gases passing through said tubes and promoting the transfer of heat from said gases.

2. In apparatus for separating the dust from the hot gases discharged from rotary Portland cement kilns and for generating steam therefrom, a vertically arranged cylindrical boiler shell provided with internal tube sheets to form a gas chamber adjacent the top of the shell and an enlarged collecting chamber adjacent the bottom of the shell, a gas conduit communicating with said gas chamber to supply hot furnace gases from a rotary cement kiln to said gas chamber and cause their passage down through said gas tubes and supply heat to the water around said tubes, a discharging flue for said gases communicating with said collecting chamber, large diameter vertical gas tubes mounted in said tube sheets and highly charged electric separating conductors extending substantially axially through said tubes and promoting the transfer of heat from said gases.

3. In apparatus for separating the dust from the hot gases discharged from rotary Portland cement kilns and for generating steam therefrom, a vertically arranged cylindrical boiler shell provided with a co-operating gas chamber adjacent the top of the shell and an enlarged collecting chamber adjacent the bottom of the shell, a discharge conveyer extending into said collecting chamber to discharge the dust collected therein, a gas conduit communicating with said gas chamber to supply hot furnace gases from a rotary cement kiln to said gas chamber and cause their passage down through said gas tubes and supply heat to the water around said tubes, a discharging flue for said gases communicating with said collecting chamber, large diameter vertical gas tubes mounted in said boiler shell and having reinforced ends extending below the same, strikers resiliently mounted on oscillating striker rods to co-operate with said reinforced tube ends and dislodge the adherent dust within said tubes and highly charged electric separating conductors extending substantially axially through said tubes separating the suspended dust from the furnace gases passing through said tubes and permitting the transfer of heat from said gases.

4. In apparatus for separating the dust from hot furnace gases and for generating steam therefrom, a vertically arranged boiler shell provided with a co-operating gas chamber adjacent the top of the shell and an enlarged collecting chamber adjacent the bottom of the shell, a gas conduit communi-

cating with said gas chamber to supply hot furnace gases from a rotary cement kiln to said gas chamber and cause their passage through said gas tubes and supply heat to the water around said tubes, large diameter vertical gas tubes mounted in said boiler shell and having ends extending below the same, strikers to co-operate with said reinforced tube ends and dislodge the adherent dust within said tubes and highly charged electric separating conductors extending through said tubes separating the suspended dust from the furnace gases passing through said tubes and promoting the transfer of heat from said gases.

5. In apparatus for separating the dust from hot furnace gases and for generating steam therefrom, a vertically arranged boiler shell provided with a co-operating gas chamber adjacent the top of the shell and an enlarged collecting chamber adjacent the bottom of the shell, vertical gas tubes mounted in said boiler shell and having ends extending below the same, strikers to co-operate with said reinforced tube ends and dislodge the adherent dust within said tubes and highly charged electric separating conductors extending through said tubes separating the suspended dust from the furnace gases passing through said tubes and promoting the transfer of heat from said gases.

6. In dust separating steam generating apparatus, a boiler shell provided with tube sheets, large area gas tubes mounted in said tube sheets and arranged substantially vertically, a dust collecting chamber communicating with the lower ends of said tubes, means to dislodge into said chamber the dust adhering to the inside of said tubes, means to pass the dust laden hot furnace gases through said tubes to supply heat to the water around them and electrostatic separating conductors extending through said tubes separating the dust from the gases passing through said tubes and simultaneously promoting the transfer of heat therefrom.

7. In dust separating steam generating apparatus, a boiler shell provided with tube sheets, large area gas tubes mounted in said tube sheets and arranged substantially vertically, means to dislodge the dust adhering to the inside of said tubes; means to pass the dust laden hot furnace gases through said tubes to supply heat to the water around them and electrostatic separating conductors extending through said tubes separating the dust from the gases passing through said tubes and simultaneously promoting the transfer of heat therefrom.

8. In dust separating steam generating apparatus, a boiler provided with large area gas passages arranged substantially vertically, a dust collecting chamber communicating with the lower ends of said passages, means to dislodge into said chamber the dust

- adhering to said passages, means to pass the dust laden hot furnace gases down through said passages to supply heat to the adjacent water and electrostatic separating conductors 5
5 tors extending through said passages separating the dust from the gases passing through said tubes and simultaneously promoting the transfer of heat therefrom.
9. In dust separating steam generating apparatus, a boiler provided with gas passages arranged substantially vertically, a dust collecting chamber communicating with the lower ends of said passages, means to dislodge into said chamber the dust adhering 10
10 to said passages, means to pass the dust laden hot furnace gases down through said passages to supply heat to the adjacent water and electrostatic separating conductors separating the dust from the gases passing 15
15 through said tubes and simultaneously promoting the transfer of heat therefrom.
10. In dust separating steam generating apparatus, a boiler provided with gas passages, a dust collecting chamber communicating with said passages, means to dislodge into said chamber the dust adhering to said passages, means to pass the dust laden hot furnace gases through said passages to supply heat to the adjacent water and electrostatic separating conductors separating the dust from the gases passing through said tubes and simultaneously promoting the transfer of heat therefrom. 20
20
11. In dust separating steam generating apparatus, a boiler provided with large area gas tubes mounted and arranged substantially vertically, a dust collecting chamber communicating with the lower ends of said tubes, means to dislodge into said chamber the dust adhering to the inside of said tubes, means to pass the dust laden hot furnace gases down through said tubes to supply heat to the fluid around them and electrostatic separating means extending through 25
25 said tubes separating the dust from the gases passing through said tubes and simultaneously promoting the transfer of heat therefrom.
12. In dust separating steam generating apparatus, a boiler provided with large area gas tubes, a dust collecting chamber communicating with the lower ends of said tubes, means to dislodge into said chamber the dust adhering to the inside of said tubes, means to pass the dust laden hot furnace gases down through said tubes to supply heat to the fluid around them and electrostatic separating means extending through said tubes separating the dust from the gases passing through said tubes and simultaneously promoting the transfer of heat therefrom. 30
30
13. In dust separating steam generating apparatus, a boiler provided with gas tubes, a dust collecting chamber communicating with the lower ends of said tubes, means to dislodge into said chamber the dust adhering to the inside of said tubes, means to pass the dust laden hot furnace gases through said tubes to supply heat to the fluid around them and electrostatic separating means separating the dust from the gases passing through said tubes and simultaneously promoting the transfer of heat therefrom. 35
35
14. In dust separating steam generating apparatus, a boiler provided with gas tubes, means to pass hot furnace gases through said tubes to supply heat to the fluid around them and electrostatic separating means promoting the transfer of heat therefrom. 40
40
15. In steam generating apparatus, a container provided with gas passages, means to pass hot gases through said passages to supply heat to the fluid in said container around said passages and electrostatic means promoting the transfer of heat from said gases. 45
45
16. In liquid heating apparatus, a liquid heater provided with substantially vertical gas passages, means to pass hot gases through said passages to supply heat to the fluid around them and electrostatic means in said passages promoting the transfer of heat from said gases. 50
50
17. In liquid heating apparatus, a heater provided with gas passages, means to pass hot gases through said passages to supply heat to the fluid around them and electrostatic means promoting the transfer of heat from said gases. 55
